UNITED STATES PATENT OFFICE.

WALTER SCOTT, OF HOOSIC FALLS, NEW YORK, AND MOSES W. MANWARING, OF BRIDGEPORT, CONNECTICUT.

SELF-EXTINGUISHING LAMP.

SPECIFICATION forming part of Letters Patent No. 291,620, dated January 8, 1884.

Application filed April 25, 1883. (No model.)

To all whom it may concern:

Be it known that we, WALTER SCOTT, of Hoosic Falls, in the county of Rensselaer and State of New York, and MOSES W. MANWARING, of the city of Bridgeport, in the county of Fairfield and State of Connecticut, both citizens of the United States, have invented certain new and useful Improvements in Self-Extinguishing Lamps, of which the following is a specification.

Our invention relates to a self-extinguishing lamp; and the object in view is to provide a lamp with means which, by the reason of the consumption of oil therein, shall automatically extinguish the flame, so that by making lamps of desired sizes or supplying a desired and predetermined quantity of oil such lamps will be extinguished after burning a stated time, whereby such lamps are adapted for use as street-lamps and for other purposes.

Further objects and advantages will appear in the following description of the construction and operation of our invention, and its novel features will be specifically pointed out in the claims.

Referring to the accompanying drawings, forming a part hereof, Figure 1 is a side elevation, partly in section, of one form of an embodiment of our invention in a lamp, looking toward the broad side of the wick-tube. Fig. 2 is an elevation, partly in section, of the same, looking toward the narrow side or edge of the wick-tube. Fig. 3 is a plan of the lamp with the top removed. Fig. 4 is a perspective of the under side of a portion of the top and the mechanism attached thereto, and Fig. 5 is a modified arrangement of details. Fig. 6 is another modification.

Like letters indicate like parts in all the figures.

A represents any suitable burner, having connected with the wick-tube extinguishing devices, which in this instance consist of two pivoted half caps or wings, A', adapted to be closed over the wick B, to extinguish the flame thereof, by raising the wire A².

So far as our present invention is concerned, we neither claim nor restrict ourselves to the form of extinguisher herein shown, but may

adapt our means to operate with any form of extinguisher, whether it is operated by devices which move in vertical or other directions.

C represents the outer or main oil receptacle or body of a lamp, and the same may be of any desired conformation.

Within the body C is located and arranged, it may be in any suitable manner, a separate floatable reservoir, D, of such construction and relative size to the body of the lamp as to permit oil to surround and to enter the same, and to retain such portion of oil as shall enter therein, and as said oil is consumed by the burning thereof to gradually rise in and upon the surrounding oil in the body of the lamp, whereby the movement of the floating reservoir may be utilized to actuate any suitable mechanism interposed between said reservoir and the extinguisher, to operate the same so as to put out the flame of the lamp. In this instance, to illustrate one form of an embodiment of our invention, the mechanism employed to convey the motion of the floating reservoir D to the extinguisher-operating device A² comprises a vertically-arranged push-bar, E, which passes through a guide-tube, f, secured to the cover or top F of the lamp-body C. To the under side of the cover or top is secured any desired counterbalanced or spring-locked pivoted lever, as G, which presents its free end downward toward the floating reservoir in such a manner that when the latter rises sufficiently high, by reason of the consumption of oil therefrom, the former is forced against the bar E and raises it against the extinguisher-operating device A².

As shown, the lever G consists of a wire bent at one end to increase its contact-surfaces, and secured at its opposite end to a plate, g, one edge of which rests in notches formed in the edge of studs or brackets g', secured to or formed on the top F, the opposite edge of said plate being connected by a spring, H, arranged in line with and secured in advance of the free end of the lever G. A portion of said edge of the plate g is bent to form a stop, g², which determines the position of the free end of the lever when in a locked position, as when the lamp has been filled and its push-bar E

pressed down. The stop, when performing its function as such, rests against the under surface of the top F, and the spring H is at that time so disposed as to exert its strain in a line 5 above the pivoted edge of the lever-plate g, and thus hold it slightly in a locked position, so that a light force exerted upon the depressed free end of the lever will change the position of the plate, in which position the spring exerts its strain in a line below the pivoted edge of the plate and throws the free end of the lever forcibly upward against the lower end of the depressed push-bar, and it in turn is forced against the extinguisher-operating device A².

15 In this instance a step or projection, I, is formed or located on the floating reservoir, so as to come in contact with the free end of the lever; but, if desired, said free end of the lever may be arranged to be operated by the 20 bottom or a side wall of the floating reservoir.

It may be desirable to connect the floating reservoir to the body of the lamp in such manner as to retain it centrally therein, and yet permit of its rising and falling for the purpose described. Certain means of connection are herein illustrated, and comprise pivotal links or bails J, arranged on any two sides of the body and floating reservoir, and adapted to operate after the manner of a gimbal-support. The pivoted ends j of the bails being inserted in slots j', formed in the walls of the floating reservoir, permits vertical and prevents undue lateral movements of the same. If desired, a spring, K, may be interposed between the bottoms of the lamp body and reservoir, for the purpose of counterbalancing the weight of the latter, in order that its rising shall depend more fully upon the quantity of oil consumed therefrom, and thus tend to 40 a more accurate predetermination of the length of time which the lamp shall be allowed to burn before being automatically extinguished.

Other connecting means between the body and reservoir will readily suggest themselves to a person skilled in mechanics, and we therefore do not limit ourselves to those above described; and, as above indicated, other means or details of motion-conveying devices may be interposed between the floating reservoir 50 and the extinguisher-operating device.

As shown in Fig. 5, the push-bar E may be connected to a horizontal lever, G, pivoted to the top F, held normally by a spring, H, against a stop, g², on a secondary pivoted lever, g, the free end of which is projected over the floating reservoir, D, so that when it rises by consumption of oil therefrom the lever G is released from the stop g², and is forced by the spring to raise the bar E, as heretofore set 60 forth. Furthermore, a weighted lever, G', as shown in Fig. 6, may be thrown over its center of support (by the reservoir D or a step, I, therein while it is ascending) and upon a secondary arm, which shall raise the lever G,

as aforesaid, and various other modified arrangements of motion-conveying devices may be employed, and are deemed as comprehended by our invention. If desired, a filling-hole, f', may be provided; but this is not essential, as our invention in no manner affects the removability of the burner for filling purposes. 70

To prevent undue splashing of oil within the reservoir, and to retain the desired quantity of oil against displacement by swaying, jarring, or any ordinary unlevel disposition 75 of the lamp, we provide the floating reservoir with a cover, L; but it is perforated centrally at l for the passage of the wick.

Having described our invention and its operation, what we claim is— 80

1. A lamp provided with a floating reservoir, an extinguisher, and intermediate motion-conveying devices, whereby the consumption of oil from the reservoir causes it to rise and extinguish the flame of the lamp, substantially 85 as herein set forth.

2. In a lamp, the combination of a floating reservoir, an extinguisher, and intermediate extinguisher-operating devices, substantially as specified. 90

3. In a lamp, the combination of a floating reservoir, an extinguisher, and an intermediate spring-locked or equivalent extinguisher-device-operating lever, substantially as specified. 95

4. The combination of a lamp-body and an internal floating reservoir with pivoted connecting-bails, to maintain it in proper relation to the extinguishing mechanism, substantially as specified. 100

5. The combination, with a lamp, C, provided with extinguishing devices A' A², of a floating reservoir, D, and an intermediate push-bar and pivoted lever, G, substantially as specified. 105

6. The combination of the push-bar E, lever G, plate g, brackets g', stop g², and spring H, substantially as shown and described.

7. The combination of the lamp-body C, reservoir D, and bails J J, pivotally secured to the body and to the reservoir in slots j' therein, substantially as shown and described. 110

8. The combination of the lamp-body C, reservoir D, having a centrally-perforated cover, L, and bails J J, substantially as shown and described. 115

9. The combination of the lamp-body C, reservoir D, having step I, lever G, push-bar E, and burner A, and operating-rod A², substantially as shown and described.

WALTER SCOTT.
